UNITED STATES PATENT OFFICE.

EDWIN C. WEISGERBER, OF LONG BEACH, CALIFORNIA.

RUN-DOWN BOX.

Application filed February 18, 1924. Serial No. 693,584.

My invention relates to a means for collecting condensed petroleum vapors and it has especial reference to an apparatus for distributing various cuts or fractions into respective containers or tanks, the object of the invention being to provide a tail or run-down box, in which the condensates from one or a plurality of condenser lines may be directed into various receptacles as they are discharged from a single nozzle or pipe or a plurality of nozzles or pipes, whereby a multiplicity of valves and valvular and other adjuncts are rendered unnecessary and superfluous, and finer and cleaner cuts may be made quickly without interference with the system.

Another object of the invention is to provide in connection with an apparatus of the general character set out, an indicating means for determining in the particular receptacle or trough different grades of condensates which are to be delivered.

Another object of the invention is to provide in connection with an apparatus of the type referred to, a convenient means constantly visible, for determining the gravities of the various condensates and thereby indicating to the observer or operator into which the particular oil is to be discharged.

Another object of the invention is to provide a tail box system in which the units thereof may be multiplied indefinitely as needs require.

Other objects will appear from the subjoined specification, in connection with the accompanying drawing, which are illustrative of one of many forms of embodiment of the invention, and in which,

Fig. 1 is a plan view showing two conjoined and intercommunicating closed tail boxes, with means connected with a source of condensate supply, and means for effecting from the outside a distribution of the condensates to various troughs within the boxes; and gravity-determining means associated with the boxes.

Fig. 2 is an end view of two boxes, one of which is shown in section.

Fig. 3 is an end view of a run-down or tail box divided into a plurality of compartments, showing a plurality of distributing nozzles severally arranged to connect with a plurality of condenser lines, and

Fig. 4 is a fragmentary, sectional detail

showing a trap and a bleeder line for a part 55 of the flowing condensate, and a hydrometer in the trap whereby changes of oil gravity may be noted.

The invention, generically viewed, consists of a closed run-down box, divided into 60 compartments and provided with a means movable with respect to said compartments to distribute condensates of varying gravities into respective compartments. Specifically my invention comprises a closed 65 chamber or box 1, having a gas vent 2, a sight door 3 on the top, a sight door 3' in the side, and having an interior division of a plurality of compartments or troughs 4, into which different cuts of condensates 70 are arranged to be discharged by the means presently set out. Each of said compartments or troughs 4, is provided with an outlet 5, through which the respective condensate may be conducted to suitable reservoirs or containers, and in order that the box unit may be multiplied, the wall 6 of same is provided with ports 7, which will correspond and register with similar ports 8 in a wall 9 of another box 10, as shown. 75 The walls of respective boxes connected in multiple are fastened together in any suitable manner, either permanently or temporarily. The transverse walls 11, with in the chamber or box 1, and forming the 80 various compartments or troughs 4, extend from the bottom of the box to about half way from the top thereof, for the purpose of enabling a discharge nozzle or pipe section 12 to be swung within the box and in 85 an arcuate plane over the compartment walls 11, and in line with each compartment.

As seen from the sectional illustration, Fig. 2, and also from the sectional illustration in Fig. 3, this nozzle or pipe section 90 12, extends and is operable in a horizontal plane, and for the purpose of this disclosure, may be connected with standpipe 13, by a swivel coupling 14, threading on said standpipe 13, which extends through the box top 100 or cover 15, and is fastened thereto in any secure manner. In the upper end of said standpipe 13, threads a packing gland 16, compressing between it and a packing seat 17, a suitable packing element 18, which surrounds a vertically disposed shaft 19. This shaft 19 is firmly attached in any manner to the swiveled nozzle or pipe section 105

12, and extends through the standpipe 13 and packing gland 16. Onto the end of said shaft 19 is fixed a lever, or handle or wheel 22, by which the swiveled nozzle 12 may be moved to direct the discharge into any of said compartments or troughs.

10 A suitable indicator 23, of any approved type or construction may be mounted upon the end of said standpipe 13, for the purpose of guiding the operator in determining the position of the swiveled pipe or nozzle 12, from the outside.

15 The handle or lever 22, is provided with an index finger 22' and co-operates with the indicating marks 23' on said indicator 23, the marks 23' representing substantially the central line of the compartments or troughs 4. To determine the time at which the nozzle or pipe 12 should be moved to discharge 20 a different cut into its corresponding trough 4, I provide a trap 24, in which is contained a hydrometer 25, viewable through a glass dome 26, mounting the trap 24. This trap 24, shown more in detail in Fig. 4, is supplied 25 constantly with a quantity of the condensate from a condenser line 27, entering the standpipe 13, above the top or cover 15, through a funneled pipe 28, extending in the path of the condensate flow. This pipe 30 28 delivers the condensed liquid to the bottom of trap 24, in which is disposed the hydrometer. The overflow of condensate collects in a trough 29, surrounding the trap 24, and from said trough 29, the condensate 35 is led back to the standpipe 13 through a pipe 30, for eventual discharge into the respective compartment. The hydrometer in the trap 24 is a reliable and accurate guide for the operator in determining the nature of the condensate flowing over from a condenser and thereby he is enabled quickly to direct the distribution of the condensed liquid to the proper trough in the box.

40 To discharge end of the swiveled nozzle 12 is provided with an extension 31, for preventing splashing of the liquid and this extension is formed with a spider 32, and a central bearing 33, which provides a suitable support for same from a ball 34, fixed or 45 formed on the end of a stem 35, which extends through the discharge end of the nozzle 12, and through a boss 36 on said nozzle. Said stem 35, is secured in place by a 50 nut 37. The extension 31, is mounted for universal movement for the purpose of permitting the discharge end to be moved past the various compartment-forming walls 11, which extend in the plane of travel of said extension 31.

55 60 Referring to Fig. 3, the general structural design and application of the invention is shown in multiple use in a single tail box, with a plurality of receiving chambers, while in Figs. 1 and 2, a single discharge nozzle is employed in a tail box with multiple com-

partments. In said Fig. 3, each of the standpipes 13, is connected with a separate condenser line, and the multiple arrangement of the nozzles 12 associated with the standpipes 13 is wholly contained within a tailbox 38, which is divided into a plurality of chambers or receivers 39. Each chamber or receiver 39 is provided with an outlet 40.

What I claim, is:

1. A tail box comprising a receptacle having a plurality of compartments, a standpipe, a condensate pipe connected to said standpipe, a pipe section swiveled on said standpipe, and means for moving said pipe section to direct the condensate flowing through same to any of said compartments. 75

2. A tail box comprising a receptacle having a plurality of compartments, a standpipe extending through the top of said receptacle, a condensate pipe connected to said standpipe above the top of said receptacle, a section of pipe mounted to swing within said receptacle and means for moving said section of pipe to direct the discharge of the condensate to any one of said compartments. 85 90

3. A tail box comprising a closed receptacle having a plurality of compartments, a standpipe extending through the top of said receptacle and connected with a condensate source, and means movable relatively to said compartments and connected to said standpipe to direct the discharge of condensate into any of said compartments, with means outside of said compartments for moving said means. 95 100

4. A tail box comprising a closed receptacle having a plurality of compartments, a standpipe extending through the top of said receptacle and connected with a source of condensate supply, a section of pipe within said receptacle and swiveled to said standpipe, means outside said receptacle and manually operable to direct the discharge of condensate into any of said compartments, and means to indicate the position of said section of pipe within said receptacle. 110

5. A tail box comprising a closed receptacle, having a plurality of compartments, a standpipe extended through the top of said receptacle, and connected with a source of condensate supply, a condensate discharge pipe connected to said standpipe, means outside of said receptacle for manually moving said discharge pipe relatively to said compartments, an index on said standpipe and 115 an indicator on said moving means co-operating with said index to indicate the position of said discharge pipe within said receptacle and with respect to said compartments. 120

6. A tail box comprising a closed receptacle having a plurality of compartments, a pipe conveying condensate to said receptacle, a nozzle having a swinging connection with said pipe and disposed within said receptacle and above said compartments, means outside 125 130

of said receptacle for moving said swinging nozzle, indicating means to determine the position of said nozzle and gravity indicating means for the condensate associated with 5 the receptacle.

7. A tail box comprising a closed receptacle having a plurality of compartments, a pipe conveying condensate to said receptacle, a nozzle within said receptacle mounted 10 upon said pipe to swing, means outside of said receptacle to swing said nozzle, indicating means to determine the gravity of the condensate, and indicating means to determine the position of said nozzle within said 15 receptacle.

8. A tail box comprising a closed receptacle having a plurality of compartments, a pipe conveying condensates to said receptacle, a swinging pipe section connected to 20 said condensate pipe, means to move said swinging pipe section to direct the discharge of condensate into any of said compartments, and an extension on the discharge 25

end of said swinging pipe section, with means for universally mounting same. 25

9. A tail box comprising a receptacle having a plurality of compartments, a pipe conveying condensates to said receptacle, a nozzle having a swinging connection with said pipe and disposed within said receptacle, and above said compartments, and means to move said swinging nozzle from the outside of said receptacle. 30

10. A tail box comprising a closed receptacle having a plurality of compartments, a pipe conveying condensates to said receptacle, a nozzle having a swinging connection with said pipe and disposed within said receptacle and above said compartments, an extension universally mounted upon the 35 discharge end of said nozzle, and means outside of said receptacle for moving said swinging nozzle. 40

In testimony whereof I have set my hand.

EDWIN C. WEISGERBER.
